CLAIM

The ornamental design for a cap, as shown and described.

DESCRIPTION

FIG. 1; is a front elevational view of the cap showing my new design

FIG. 2 is a rear elevational view thereof;

FIG. 3 is a left side elevational view thereof;

FIG. 4 is a right side elevational view thereof;

FIG. 5 is a top plan view thereof;

FIG. 6 is a bottom plan view thereof;

FIG. 7 is a perspective view thereof;

FIG. 8 is another perspective view of a second embodiment of the cap showing my new design; and,

FIG. 9 is a left side elevational view of FIG. 8.

The broken line showing of the crown is for illustrative purposes only and forms no part of the claimed design. But the broken lines within the shoe(the indicia) represent stitches and form part of the claim.
